UNITED STATES PATENT OFFICE.

MICHAEL F. SULLIVAN, OF SAN FRANCISCO, CALIFORNIA, ASSIGNOR TO GERTRUDE A. MARGESON, OF SAN JOSE, CALIFORNIA.

INDICATOR.

1,351,707.

Specification of Letters Patent. Patented Aug. 31, 1920.

Application filed August 22, 1918. Serial No. 250,961.

To all whom it may concern:

Be it known that I, MICHAEL F. SULLIVAN, a citizen of the United States, residing in the city and county of San Francisco and State of California, have invented new and useful Improvements in Indicators, of which the following is a specification.

This invention relates to an indicator which is particularly adapted for installation on trains or street cars for the purpose of indicating the name of the station or street.

The object of the present invention is to provide a practical street car indicator wherein the various streets or stations at which stops are made are indicated on a traveling belt, or equivalent carrier; the belt being driven by a motor which is set in operation by appropriate means controlled either by the car or the conductor, or other operator, and providing means whereby the motor is automatically stopped through the medium of the belt, to display the desired street or station indication. Another object of the invention is to provide a pair of switches which are automatically operated by the belt and intermittently opened and closed by same, and which switches are so connected with the motor that the circuit through same will be automatically opened when a street name is brought into register with a suitable display opening. Another object is to provide means which may be either manually or automatically operated for closing the circuit through the motor when a new street name is to be displayed. Another object of the invention is to provide a novel form of transmission through which the display belt may be driven in either direction. Further objects will hereinafter appear.

The invention consists of the parts and the construction and combination of parts as hereinafter more fully described and claimed, having reference to the accompanying drawings, in which—

Figure 1 is a side elevation of the indicator showing the casing in section.

Fig. 2 is a plan view of same.

Fig. 3 is a cross section of the clutch on line $\alpha-\alpha$, Fig. 2.

Fig. 4 is a diagrammatic view of the motor circuit and controlling switches.

Referring to the drawings, A indicates a base plate, on which is secured a pair of

frame sections 2 and 3. Suitably journaled in said frame are a pair of driven rollers 4 and 5 and a pair of idlers 6 and 7. 8 indicates a belt constructed of any suitable material, such as paper or cloth fabric, which is carried by the rollers 4 and 5 and guided by the idlers 6 and 7, and 9 is a casing which is adapted to entirely inclose the mechanism, as indicated in Fig. 1.

The driven rollers are in this instance driven through means of a reversible electric motor B and connection between same and the rollers 4 and 5 will be as follows:

10 indicates a horizontally positioned shaft which is journaled, as at 11, in a bracket member 12 secured upon the base. Secured upon one end of said shaft is a beveled gear 13 which intermeshes with a similar gear 14 secured upon the motor shaft, and secured to the opposite end of shaft 10 is a worm gear 15 which intermeshes with a worm wheel 16, secured to a shaft 17, which in turn is journaled in the main frame. Loosely mounted on said shaft is a pair of sprocket wheels 18 and 19 and connecting said sprockets with a pair of sprockets 20 and 21 secured upon shafts 22 and 23, upon which rollers 4 and 5 are mounted, are chains 24 and 25.

Suitably secured to the inner faces of sprockets 18 and 19 are pins 18^a and 19^a. Turnably mounted on the shaft 17, intermediate of the sprockets 18 and 19, is a clutch member 26, and projecting from either end of said clutch are pins 18^b and 19^b. The clutch 26 consists of a sleeve in which is cut an angularly positioned slot 27. Secured to shaft 17 and projecting through said slot is a pin 28^a. Surrounding the sleeve and frictionally engaging same is a pair of friction clamp arms 29, the tension of which may be regulated by a screw 30, said clamp arms being secured, as at 31, to the bracket 12.

Motor B, as before stated, is of the reversible type and can, therefore, be driven in either direction. A drive transmitted through gears 14—13 and 15—16 in one direction will first cause pin 28^a to travel from one end of the slot 27 in the clutch sleeve to the other. This causes the sleeve to move lengthwise on shaft 17, pulling pin 19^b out of engagement with pin 19^a on sprocket 19 and similarly bringing pin 18^b into engagement with pin 18^a on sprocket 18. The lon-

5 longitudinal movement of the sleeve 26 takes place while pin 28 travels from one end of the slot to the other; sleeve 26 being prevented from rotating at this moment for the simple reason that it is held against rotary movement by the clamp arms 29. The frictional engagement of said arm is, however, not sufficient to hold the sleeve against rotation when pin 28 reaches the opposite end 10 of the slot. Power is then transmitted through shaft 17, pin 28, sleeve 26 and pins 18^b and 18^a to sprocket 18 which is again transmitted through chain 25 to sprocket 21, with connected shaft and roller 4, in the direction of arrow *a*. The belt will thus be 15 unwound from roller 5 and pass over idlers 7 and 6 to be wound on roller 4.

20 The sprocket 19 being loosely mounted on the shaft 17 will thus simply act as an idler and will otherwise be inactive, as far as transmitting power is concerned, while power is being transmitted to roller 4. However, it can easily be seen that the moment 25 motor B is reversed the pin 28 will immediately travel to the opposite end of slot 27 and force the sleeve 26 longitudinally into engagement with the sprocket 19. Power will then be transmitted through shaft 17, pin 28, sleeve 26 and pins 19^b and 18^b to 30 sprocket 19 and through the chain 24 and sprocket 20 to shaft 22, upon which roller 5 is mounted. The direction of the belt will thus be reversed and will consequently unwind from roller 4.

35 The reversible motor, together with the automatic clutch indicated at 26, makes it possible to drive the belt in either direction. This is of great importance in connection with street car service, as it is necessary to 40 drive the belt in one direction when a car is moving in one direction and it will consequently be necessary to reverse the travel of the belt when the car is returning. The reversing of the motor is accomplished 45 through means of an ordinary reversing switch, indicated at 32, and means have also been provided for automatically opening and closing the circuit through the motor to produce or transmit an intermittent drive 50 to the belt 8 whether this be traveling in one direction or the other.

55 By referring to Fig. 2, it will be seen that the names of the streets are printed or otherwise applied to the surface belt, as indicated at 33. Each street name is brought into register with a display opening or window 34 formed in the front of the casing, and means have been provided for automatically stopping the belt and motor the moment a street name is brought into register with said window. This is accomplished by 60 the following mechanism:

65 35 and 36 indicate in general a pair of switches which are operated by the belt through the following means:

Each switch consists of a pair of spring contact members 37-38, and pivotally mounted on the main frame, as at 39 and 40, is a pair of rocker-arms 41 and 42, one for each switch. Suitably secured to the outer 70 end of each lever arm is a roller 43, and secured on the edges of the belt are a plurality of raised projections 44 and 45; the projections 44 being so positioned as to engage with the roller on arm 41, while the projections 45 will engage with the roller on arm 42. There is one projection for each street and name and these are staggered with relation to each other. That is, projection 44, which registers with "I St." (see Fig. 2) is 75 offset with relation to projection 45 on the opposite side of the belt which registers with "J St." Similarly, projection 44 which registers with "K St." is offset with relation to projection 45 which registers with "L St." etc. 80

85 The inner end of each rocker-arm is turned outwardly, as indicated at 46, to bring the end of the rocker-arm directly above the flexible contact members of the respective switches 35 and 36 with which they are connected. The operation of this part of the mechanism will be as follows:

90 Motor B having been started will consequently transmit movement to drive the belt. The belt moving in a certain direction will consequently bring one of the belt projections into engagement with roller 43 of arm 42, and will rock this about the pivot 40, causing the outer end to move downward in the direction of arrow *b*, and force the flexible contacts 37 and 38, of switch 36, into engagement with each other. Contacts 44 on the opposite side of the belt being offset, with relation to contact 45 which is now 95 in register with roller 43, will consequently permit arm 41 to remain in the raised position. Contacts 37 and 38 of switch 35 will thus remain in the normal or open position. 100

105 The switches 35 and 36 are automatically opened or closed through means of the projections 44 and 45 and arms 41 and 42. Said switches are in turn connected with the motor circuit in such a manner that one opens a circuit through the motor while the opposite switch closes a circuit through the motor which is closed in this instance by a manually operated switch, indicated at 47. The position of the automatically operated switches 35 and 36, with relation to the motor circuit and the manually controlled switch 47, will be more fully explained by referring to Fig. 4.

110 The reversible motor, indicated at B, is in this instance, connected through a wire 125 48 with the reversing switch indicated at 32, which in turn is connected through a wire 49, with a suitable source of electric supply, as the overhead wire of the car. The other terminal of the motor is grounded through 130

a wire 50. Connected through a wire 51 with wire 48 is the manually controlled switch 47, which, in this instance, is provided with two terminals 52' and 52. Terminal 52' is connected through a wire 53 with the flexible contact 37 of switch 35, and the terminal 52 is connected through a wire 54 with the flexible contact 38 of the switch 36. The upper terminal 38 of each switch 35 and 36 is in turn connected through a wire 55, and this wire is in turn connected through a wire 56 with the wire 50, which is grounded, as before stated.

The circuit through the motor, when revolving in one direction, which direction is controlled by the reversing switch 32, can be traced as follows:

For the purpose of tracing the circuit it will be necessary to assume that the contacts 37 and 38 of switch 36 are closed and that the motor is standing still. The conductor seeing that the car has just passed a street will now operate switch 47 to start the motor so that the belt may be moved to indicate the name of the next street. The conductor will in this instance, move the switch arm into engagement with the contact 52'. This closes the following circuit:

Current coming in through wire 49 and reversing switch 32 will pass through wire 48, which is connected with one terminal of the motor. It will then pass through the motor and out the opposite terminal and through wire 50 pass to the ground. The circuit being thus closed through the motor will remain closed until the belt has traveled sufficiently far to bring the succeeding street into register with the window 34. Projection 44 will in this instance, move into engagement with the rocker-arm 41 and consequently close a circuit through the flexible contacts 37 and 38 of switch 35.

Projection 44 which previously held the contacts of switch 36 closed will now move out of register with arm 42, which operates switch 36, and will permit this to remain in the open position. The closing of switch 35, through means of the projection 44 on the belt, establishes a new circuit which can be traced as follows:

Current entering through wire 49 and reversing switch 32 will pass through wires 48 and 51, through switch 47, terminal 52', wire 53, contacts 37 and 38 of switch 35, wires 55 and 56 to wire 50 which in turn is connected with the ground.

The circuit just described which is closed by switch 35 offers less resistance to the passage of the current than the motor. The current will consequently pass through this circuit to the ground and permit the motor to remain stationary. The current will continue to flow through the circuit until the operator again operates the switch 47. This is, of course, not moved until it is necessary

to indicate the name of the next street or station. It is accomplished by moving the lever into engagement with terminal 52. The movement of the switch lever from terminal 52' to terminal 52 immediately breaks or opens the circuit through switch 35. The current entering through wire 49 will thus again pass through motor B to the ground, causing the belt again to move to a new name to be displayed.

The circuit through the motor is, however, again opened the moment the new street name is brought into register with the window 34, as projection 45 will now be brought into register with arm 42 and cause this to close the flexible contacts 37 and 38 of switch 36. The motor circuit is immediately opened when the switch 36 closes, for the simple reason that the current will again follow the path of least resistance which passes through wires 48 and 51, through switch 47, terminal 52, wire 54, switch 36, wires 55 and 56 and wire 50 which connects with the ground. The motor is consequently stopped as no current passes through same, and the belt will remain stationary until the lever of the switch 47 is again moved into engagement with the contact 52'.

From the foregoing description it can be now seen that a circuit through the motor is closed by the manually operated switch 47, and that the motor is automatically stopped by either the automatic switches 35 or 36 which may be controlled by the projections formed on the belt. An intermittent drive is thus transmitted to the belt.

For the purpose of stopping the motor, with connected transmission and belt, the moment a street name is brought into register with the window or display opening a number of friction shoes have been provided. The rollers 4 and 5 are, with this object in view, provided with a spool-like flange at each end, as indicated at 4^a and 5^a, respectively, and contacting with the outer faces of said flanges are friction arms 4^b and 5^b, respectively.

The motor is immediately stopped the moment the circuit through same is opened through the means of one or the other of the switches 35 and 36, as the current is bypassed to the ground and the belt, together with the motor, is further stopped by the action of friction arms 4^b and 5^b. These prevent the parts from running idle after the current has been by-passed.

The indicating mechanism here shown is simple in construction and positive in operation. It is automatically stopped through switches 35 and 36 and may be driven in either direction through means of the reversible motor, which in turn is controlled by the switch 32. The starting of the motor is here shown as controlled by a manually operated switch 47. I do not, however, wish

to limit myself to a manually operated switch as it is evident that the automatic switch might be utilized for this purpose.

The materials and finish of the several parts of the mechanism are such as the experience and judgment of the manufacturer may dictate.

Having thus described my invention, what I claim and desire to secure by Letters Patent is:

1. In a street indicator, a frame, a pair of rollers borne by the frame and having a belt engaged therewith, means to drive the rollers including a motor, and means to stop the motor including a contact device, means to connect said device to the frame, an L-shaped rocker arm having one end horizontal and arranged above the device and formed to close the device, said rocker arm being pivoted at its angle to the frame and having its other end depending downwardly from the pivot, and projections on the belt engageable with said other end of the arm to raise the latter, the depending end of the rocker arm being formed so as to normally maintain the horizontal end thereof out of engagement with the contact device.

2. In a street indicator, a frame, a pair of rollers borne by the frame and having a belt engaged therewith, means to drive the rollers including a motor, and means to stop the motor including a contact device carried by the frame and extending outwardly from a side thereof, an L-shaped rocker arm having one end portion thereof horizontal and extending outwardly of the frame and provided with a depending part to overlie and engage the contact device to close the latter, said rocker arm being pivoted at its angle to the frame and having its other end extending beyond the frame and depending downwardly from the pivot, and projections on the belt engageable with said other end of the arm to raise the latter, the depending end of the arm being formed so as to normally maintain the horizontal end thereof out of engagement with the contact device.

In testimony whereof I have hereunto set my hand in the presence of two subscribing witnesses.

MICHAEL F. SULLIVAN.
